UNITED STATES PATENT OFFICE.

ALGOT A. WICKLAND, OF CHICAGO, ILLINOIS.

COAL PULVERIZER.

Application filed December 19, 1923. Serial No. 681,455.

My invention relates to improvements in coal pulverizers, and has for its objects the production of a device of the kind described, wherein the coal is elevated to the machine from a hopper or other suitable source of supply, separating the metals and other foreign substances therefrom and removing a portion of the moisture content during such elevating of the fuel.

10 Other objects of my invention are to provide a machine of the kind described which shall be of minimum size, large capacity, simple and substantially constructed, and wherein the pulverizer is adapted to be installed and operated in close proximity to the furnace in which the pulverized coal discharged from the pulverizer is to be consumed.

15 Other objects of my invention are to provide for the ready removal of the wear elements and to compensate for the wear of these parts so that the cost of renewal and maintenance may be reduced to a minimum.

Referring more particularly to the drawings in which like reference characters indicate like or corresponding parts,

Fig. 1 is a longitudinal cross-section view through the pulverizer.

Fig. 2 is a rear elevation thereof.

30 Fig. 3 is a fragmentary cross-section through the coal feeding trough.

Fig. 4 is an end elevation of the pulverizer shown in connection with the furnace and source of coal supply.

35 Fig. 5 is a cross sectional view of the pulverizer casing or housing with the rotary impact discs removed.

Fig. 6 is an elevation of the rotary impact disc assembly, taken from one end.

40 Fig. 7 is a similar view, taken from the other end.

Fig. 8 is an enlarged fragmentary side elevation of the pulverizer rods and discs.

Fig. 9 is a top plan view of the parts 45 shown in Fig. 4; and

Fig. 10 is a diagrammatic view of the gears for actuating the rotary valve.

Referring more particularly to the drawings, 1 indicates a furnace or other similar structure that is to receive the pulverized fuel that is to be burned therein; the same having an inlet 2. A pulverizer 3 is arranged at any suitable point, preferably in close proximity to the furnace as shown more particularly in Figs. 4 and 9. A hopper 4 may be located at any suitable place

as shown in Fig. 4, the same in the present embodiment being shown as a floor hopper.

The pulverizer itself comprises a supporting frame or base casting 5, of any suitable size and shape, having a fuel intake 6 at its upper end and a discharge outlet 7, also preferably located adjacent the upper end thereof; the latter leading to the furnace intake 2 by means of a conduit 8. 65 The outer end of the chamber housing or base casting has a removable cover 9 therefore so as to provide easy access to the parts within the chamber when the occasion arises. 70

Arranged within the chamber 10 of the housing are a plurality of rings 11 of progressively varying diameters, these rings being concentric and arranged longitudinally in a series. A web 12 may be provided within the chamber to secure the rings 11 thereto; bolts 13 being used for removably holding the rings in place. The inner peripheries of the rings and one of their side faces are roughened or corrugated as 75 at 14 and 15, the former indicating the peripheral corrugations and the latter the end corrugations. The largest ring need not have the end face corrugations, if so desired. 85

The rotary shaft 16, driven by any suitable source of power, is arranged to extend into the chamber 10, the free end of the shaft being adjacent the open end of the housing so that when the cover plate 9 is 90 removed, access may be had thereto.

Arranged axially upon the shaft 16 within the chamber are a series of spaced discs 17 to 21 inclusive, there being 5 discs in the construction shown, although the exact 95 number of discs is optional and dependent upon the number of stages of pulverizing desired.

Extending longitudinally through the discs, the latter being removably keyed to 100 the shaft, are a plurality of series of pins 22, there being a series of pins for each of the rings 11. Each series of pins is arranged annularly and extends parallel to and closely adjacent the inner corrugated 105 face of its co-operating ring 11, as shown more particularly in Fig. 1.

The pins are rotatably mounted through apertures in the discs and are secured in place by means of nuts 23 or the like on 110 the outermost disc 21. It will be apparent that the pins may be partially rotated for

adjustment after loosening the nuts 23, and then tightening the same.

The pins of the adjacent series are of different lengths, the pins closest the shaft 16 and coacting with the smallest ring being the longest. The outermost disc 21 is spaced from the cover plate 9 and has vanes or blades 24 at its periphery and projecting into said space so as to set up air currents when the shaft is revolved. Additional blades 25 may be provided between the end discs 20 and 21 at their periphery.

The fuel is delivered into the chamber 10 through the inlet 6 in a manner to be hereinafter described, the same entering the spaces between the grinding rings and the rotating pins and becoming pulverized before it is discharged upwardly throughout outlet 7.

20 The corrugations on the grinding rings serve to retard the flow of the fuel past the grinding elements and insure that the grinding will be evenly and efficiently done. As the grinding surfaces of the pins 22 become worn they may be partially rotated and locked in their new position of adjustment so as to compensate for wear, thus providing a new grinding or impact surface as fast as the old surface becomes worn. It is to be understood that the pins 22 may be of any cross-sectional shape, as for instance circular, triangular, hexagonal, or the like.

When the grinding pins become worn on all sides adjacent their co-operating grinding rings, they may be removed and shortened or cut off for insertion into the adjacent shorter series of pins. That is, when the pins of the lowest series, which in this case are the longest pins, become worn at their ends, they are cut off to the length of the next shorter pins and are inserted or substituted for the latter. In practice the wear will be substantially uniform on all pins so that when the replacing is done the pins are merely shortened and each moved up to take the place of the next shorter pins.

50 The cover plate 9 is dished out or enlarged to provide a chamber 26 substantially concentric with the discs adjacent their centers, and a rib or flange 27 is provided on the cover plate to extend laterally inwardly to closely adjacent, but not in contact with, the end disc 21.

A conduit 28 leads from the chamber 26 to a separator 29 as shown more particularly in Fig. 1. At this point it may be mentioned that the end disc 21 has one or more openings 30 therethrough adjacent its center as shown in Fig. 7, so that when the shaft 16 is rotating, the fans 24 and 25 will cause a suction inwardly of the chamber 26 through the apertures 30 and outwardly of the discharge outlet 7, thus creating a suction in the separator 29.

65 The chamber 26 may be considered as a

high suction chamber, while the chamber formed between the rib 27 and the outer periphery of the disc 21 will be a low suction chamber.

Wickets 31 and 32 may be provided in the cover plate 9 to control the admission of atmospheric air to the high suction and low suction chambers and regulate the suction therein.

In operation the coal discharged through the inlet 6 will fall into the chamber 10 and, due to the suction therein and to the centrifugal force of the pins, will be drawn through the co-operating grinding or impact surfaces in series or in successive stages, and thence be discharged through the opening 7.

A slowly driven rotary valve 33 is arranged in an extension chamber 35 beyond the discharge outlet 7, so that the heavier particles of pulverized coal may drop or collect therein. The underside of the rotary valve communicates with the intake side of the chamber 10 so that as the valve is revolved the coal therein will drop into said chamber and be again fed to the grinding elements. Any suitable means may be provided for driving the valve 33, as for instance the gears 34 shown in Fig. 10.

The chamber 35 into which the pulverized fuel is discharged before its admission to the conduit 8, is under considerable static pressure due to the action of the grinding elements, and the fan blades, and therefore the rotary valve 33 forms an effective seal between this chamber and the coal feeding chamber 10 which is under a partial vacuum. A hinged baffle plate 36 may be arranged in the chamber 35 to retard the flow and circulation of air set up by action of the fan blades, this baffle plate being adjustable from the outside of the casing.

The separator 29 discharges into a trough 37, past a counterweighted gate or valve 38, hinged at 39 and counterweighted as at 40. When a sufficient amount of coal has collected above the gate 38 the weight of said coal will open same and permit the coal to fall into trough 37.

An overflow pipe 41 is provided leading from the separator to return the surplus coal to hopper 4. The pipe 41 may be provided with a hinged damper 42 therein to prevent atmospheric air entering the separator, the weight of the coal opening the damper.

In the trough 37 is mounted a pusher or scraper 43 on a rod 44, said rod being given a reciprocating movement by means of drive mechanism 45 shown in Figs. 1 and 2. Adjusting means 46 may be provided to vary the stroke of the pusher and so control the amount of coal discharged from the trough at each reciprocation thereof.

The coal in the hopper 4 is discharged into a trough 47 having a screw conveyor 48 or other suitable device for the purpose. The

discharge end of the trough 47 is open as at 49 and a suction pipe 50 communicates with said discharge end of the trough and extends upwardly therefrom to the separator 29 which it enters adjacent the upper end and tangentially thereof. (See Figs. 1 and 2.)

A gate 51 is hinged to the intake end of the suction pipe 50. The suction within the separator induced by the suction through the conduit 28 leading from the high suction chamber 26 is sufficient to draw the coal from the trough 47 upwardly through the conduit 50, discharging it into the separator 29.

The burner at the inlet to the furnace may be of any suitable construction and does not form a part of this invention.

In order to supply auxiliary air to the furnace to support combustion therein said air may be admitted through pipe 55, the mixture of pulverized fuel and air being carried from the extension chamber 35 by means of the conduit 8. As has been hereinbefore described, the coal is fed into the hopper 4, carried upwardly through the pipe 50, discharged into the chamber 10 of the pulverizer through the inlet 6, where it is engaged by the rotating pins. The action of the grinding pins throws the coal outwardly against the grinding rings and pulverizes it in a series of stages after which it is discharged upwardly into the extension chamber 35 and passes through the conduit 8 into the burner.

The ratio between the fuel and air may be varied as desired, but in order to secure the best results at the burner this ratio must be kept constant.

It is to be noted that the pins at the first stage of grinding are spaced a farther distance from the co-operating surface of the stationary grinding ring than the next set of pins, the next set of pins is spaced closer to the co-operating grinding surfaces of its coacting ring than the pins of the next stage, and so on, because as the fuel passes through the successive stages of grinding it is of progressively increasing fineness.

What I claim as new and desire to secure by Letters Patent is:

1. In a device of the kind described and in combination a pulverizer comprising a housing having an inlet and outlet for the material, a rotary driven shaft therein, a plurality of series of pins driven by said shaft, and grinding rings, one spaced about each series of pins, the said rings and the co-operating ends of said series of pins being arranged in stepped relation.

2. In a device of the kind described, the combination of a pulverizer comprising a housing provided with an inlet and outlet, a drive shaft therein, a plurality of series of pins operatively connected to said shaft and

driven thereby, and an impact ring spaced from each series of pins and surrounding the same, the edges of certain impact rings being adjacent to the ends of the pins of the next adjacent series of pins.

3. In a device of the kind described comprising a pulverizer housing having an inlet and outlet, a rotary drive shaft therein, a plurality of series of annularly arranged pins driven by said shaft, impact rings arranged in said housing, each surrounding one series of said pins, said rings and the cooperating ends of said pins being arranged in stepped relation, certain of said rings having an edge adjacent to the ends of the pins of the next series.

4. In a device of the kind described comprising a pulverizer housing having an inlet for the material and an outlet for the pulverized material, a drive shaft therein, a plurality of discs spaced longitudinally of said shaft and driven thereby, a plurality of series of pins annularly arranged through said discs, the pins of adjacent series being of progressively varying lengths, and a series of grinding rings each coacting with and spaced from each series of annular pins.

5. In a device of the kind described, comprising a pulverizer housing having an inlet and outlet for material, a driven shaft therein, a series of discs spaced longitudinally of said shaft and driven thereby, a plurality of series of pins extending parallel to said shaft, each series arranged annularly and the adjacent series being of progressively varying lengths, stationary grinding rings co-operable with said annular series and spaced concentrically therefrom and means for adjusting each of the pins individually to compensate for the grinding wear thereof.

6. In a device of the kind described, comprising a pulverized housing having an inlet and an outlet, a rotary drive shaft therein, a plurality of annularly arranged series of pins driven by said shaft, a series of corrugated impact rings, arranged in stepped relation and spaced from the series of pins, respectively, and arranged to coact therewith.

7. A pulverizer comprising a housing having an inlet and an outlet, a drive shaft, a plurality of series of annularly arranged pins driven by said shaft, a series of grinding rings spaced from each series of pins, said rings corrugated about their inner peripheries and at their outer faces, the adjacent series of pins being of progressively varying lengths, and means for inducing suction outwardly of said outlet.

8. A pulverizer comprising a housing having an inlet and an outlet, a drive shaft therein, a plurality of discs of progressively increasing diameters spaced longitudinally of said shaft and movably secured thereto,

a plurality of series of pins arranged annularly through said discs, the adjacent series being of progressively varying lengths, all of said pins removably secured to one of said discs, a series of grinding rings each surrounding a series of pins, and a movable cover plate on said housing whereby access may be had to the pins and said shaft.

9. A pulverizer housing having a removable end cover, discs in said housing arranged substantially parallel to said cover, grinding elements carried by said discs, fan members carried on said grinding discs, a separator to receive a supply of coal which discharges into said pulverizer housing, a conduit opening into said separator at one end, and leading through said cover plate at the other end, and a continuous rib extending inwardly from said cover plate to closely adjacent the grinding discs to form a suction chamber therewith.

10. In a device of the kind described and in combination, a pulverizer housing having a removable cover plate at one end, a separator communicating with said housing for admitting material thereto, an outlet leading from said housing, discs within said pulverizer, a drive shaft carrying said discs, grinding elements mounted on said discs, a rib on said cover plate and extending inwardly to closely adjacent the end disc, said last mentioned disc having apertures therethrough, fan blades carried by said discs adjacent the periphery thereof to induce flow through said outlet, and a conduit between said separator and cover plate, said conduit entering said cover plate radially inwardly of said rib.

11. In a device of the class described, a housing, a pulverizer in said housing, a separator chamber above said housing, an outlet for the pulverized material joining said housing to said chamber, means for creating a blast of air through said outlet, a conduit extending from said chamber for the passage of finer pulverized particles, a rotary valve

in the bottom of said chamber for returning the coarser particles to the intake side of said pulverizer, and an adjustable baffle in said outlet for controlling the velocity of the air current therethrough and the coarseness of the material passing through said conduit.

12. In a device of the class described, a pulverizer housing, a drive shaft therein, a plurality of discs spaced longitudinally of said shaft and driven thereby, a plurality of series of beaters annularly arranged and carried by said discs, impact rings arranged in stepped relation, each ring surrounding one series of said pins, the said discs being arranged to terminate adjacent to the inner surface of said rings, respectively, whereby the material to be pulverized is directed by said discs into engagement with the said rings.

13. In a device of the class described, a pulverizer housing, a drive shaft therein, a plurality of discs spaced longitudinally of said shaft and driven thereby, a plurality of series of beaters annularly arranged and carried by said discs, impact rings surrounding the operative ends of the beaters of said series, respectively, the said rings and beaters being arranged in stepped relation, the said discs being arranged to terminate adjacent to the inner sides of said rings, respectively.

14. In a device of the class described, a housing, a pulverizer in said housing, a material receiving chamber, a passageway joining said chamber to said housing, a source of supply of material to be pulverized below said chamber, a conduit joining said chamber to the said source, and means included in said pulverizer adapted to create a suction through said passageway whereby the said material is raised by suction into said chamber.

In testimony whereof, I have hereunto signed my name.

ALGOT A. WICKLAND.
